UNITED STATES PATENT OFFICE.

JAMES T. McCABE, OF NEW YORK, N. Y., ASSIGNOR TO THE McCABE MANUFACTURING COMPANY.

DOOR-HANGER.

SPECIFICATION forming part of Letters Patent No. 534,966, dated February 26, 1895.

Application filed August 25, 1894. Serial No. 521,317. (No model.)

To all whom it may concern:

Be it known that I, JAMES T. McCABE, a citizen of the United States of America, residing in the city, county, and State of New York, have invented certain new and useful Improvements in Hangers for Sliding Doors, of which the following is a specification.

The object of this invention is to provide a traveling hanger, primarily designed for doors, but possessing features which are applicable as well to hangers by which other objects besides doors are suspended and carried along. They might be applied, for example, in telpher systems. The novel features are the form of the tubular track, the location and construction of its supports, the spherical roller, the adjustable character of its journal, and the manner of attachment to the door. These several features are shown embodied in the following specific construction, which is applied to a door constructed to slide into a pocket in the wall; but it is obvious that they can be otherwise applied.

In the accompanying sheet of drawings, Figure 1 shows my invention applied to a parlor door, a portion of the door casing being broken away. Fig. 2 is a vertical section through the axes of the roller and hanging strap, showing the mode of attachment to the door. Part of the roller is shown in elevation. Fig. 3 is a vertical cross section through the tubular track, and through one of its supporting brackets. Fig. 4 is a perspective view of the hanging strap, its roller, and an upper corner of the door. Fig. 5 is a perspective view of a portion of the tubular track, and one of its supports. Figs. 6 and 7 are detail views of a modification.

The tubular track T consists of a piece of sheet metal bent into a tubular form, but the two edges instead of meeting are turned outward at right angles to the adjoining surface of the tube. This brings the flanges f radial to the tube since the tube is circular. As the roller of the hanger in traveling through the tube bears its weight against the tubular track along the edges or ways w w, it is therefore to these parts or ways of the tube that the flanges should be made perpendicular, or nearly so, so as to stiffen the tube and assist in sustaining the load. As the flanges are

turned outward and downward, and the slot in the tube is on the under side, no water or dirt can be trapped in the tube.

The track T is held in place by suitable supports which are fastened to the underside of a part of the beam or spreader B which forms a part of the doorway. Each of these supports consists essentially of a nut N and screw S; but in order to strengthen the tube where the screw passes through, it is partially encircled by a collar C, provided with a boss C² which steadies the shank of the screw and into which its head is recessed. The height of the spreader B above the door jamb and the top of the door varies considerably in different constructions. This is provided for in the adjustment, but instead of providing it all by length of screw, it is obtained in part by recessing the nut on one side in order that it may receive the boss C² to permit the tube to more nearly approach the jamb and offsetting the flange by which it is attached thus dishing it. If the spreader is close down to the jamb the former is recessed to receive the nut and it is fastened as shown in Fig. 3; but if the spreader is higher up, then the nut is reversed, and attached in this reversed position, as shown in Fig. 5.

In applying the track to hanging a door which slides into a pocket, it is necessary that the end of the track project into the pocket, where it is inaccessible. In such cases in accordance with my invention the track is adjustably supported at two points, one at one end and the other near the middle of the track, which points are located over the doorway. The screws in the support can then be reached with a screw-driver, through the opening between the jambs. Any departure of the track from level by unequal settling of the building or otherwise can thus be readily corrected without the removal of any of the wood-work. The strength of a track constructed as hereinbefore described is such that the inner end is held rigid by the two supports, located as stated, one near the middle and the other at its opposite end.

The roller R which travels in the tubular track is spherical. Although made in two hemispherical parts, a b for reasons which will be noticed later, these two are firmly fastened

to each other so as to form a simple spherical roller. It is important that the parts be thus connected to prevent them from spreading and binding in the tube, as they might if separate and independent of each other.

Sometimes the conditions under which the hanger is used require that the tubular track be curved in a horizontal plane, as for example, when used in a telpher system or for a door which travels along a curved wall. Under such circumstances the outer hemisphere of the roller will traverse a greater distance than the inner one, but can revolve no faster because the two are rigidly connected. Usually when two wheels rigidly connected travel on a curved track there is a slipping on one side, but in this system, the wheels being hemispherical, the difference of velocity can be compensated for so that both sides will roll without slipping. This is because the door in swinging around the curve, tilts the hanger slightly and brings the hemisphere on the inner side of the curve to bear on a part of its surface where the periphery is smaller. This can be assisted by shifting the slot in the track slightly toward the inner side of the curve.

The spherical roller has a ball-bearing journal constructed so that it is adjustable for wear. The hanger strap H is formed into a ring at its upper end which has a ball-groove on its inner periphery. Each of the two hemispherical parts a and b, of the roller, has a central conical boss a' or b' on its flat face, forming a beveled bearing surface, so that when the two parts are brought together an annular groove with a V-shaped bottom is formed, in which the steel balls P are contained.

A screw t projects from the center of one of the parts a, into and through the other part b, the two parts being screwed together until the balls are snugly inclosed between the beveled faces of their central bosses and the groove in the ring of the hanger strap. A lock-nut l contained within a cone shaped recess in the part b, holds the two parts together. The roller with the adjustable ball-bearing groove is thus complete with but three pieces.

The hanger strap is formed into a rod and threaded at its lower end. On the thread are two nuts. The top of the door D is mortised, and each mortise is covered by a plate K which has a slot n connecting with an opening o. The door can be detached from the hanger strap, if desired, by simply slackening the upper nut, and slipping the strap to the opening, through which the lower nut can pass. By running the nuts up or down on the strap, the height or level of the door is readily adjustable. This simple construction thus serves the two purposes of detaching and adjusting.

Fig. 6 shows in perspective and Fig. 7 in longitudinal section a modification of the plate K in which the slot is lateral to the door and the enlargement o is omitted. It is par-

ticularly applicable to outside doors like car doors, &c., the object being to provide for lateral as well as vertical adjustment of the door relatively to the track on the under side of the plate K'. Along the sides of the slot n' are brackets q q on the plate, which hold the lower nut from turning.

Without limiting myself to the precise details shown, what I claim as new, and desire to secure by Letters Patent of the United States, is—

1. A hanger track consisting of a single piece of sheet metal formed into a slotted tube and having its contiguous edges bent outward, substantially as described.

2. In a traveling hanger, the combination of a hanging strap, a roller journaled thereto, and a track formed of sheet metal bent into a circular tube with a slot on its under side, the inner sides of the tube adjacent to the slot serving as ways for the roller, and the sheet metal adjacent to these ways being bent outwardly substantially at right angles, substantially as described.

3. The combination with a slotted track, of a collar partially encircling the track and having a boss thereon, of a reversible nut having a recess upon its one side to receive the boss upon the collar and provided with an offset attaching flange, and a screw passing through the boss and taking into the nut, substantially as described.

4. The combination with a slotted tubular track, of supports therefor adjacent to the middle portion and one end of the track, and adjustable connections between the track and the said supports, whereby the position of the middle portion and the said end of the track may be adjusted, thereby effecting the adjustment of the otherwise unsupported end thereof, substantially as described.

5. The combination with a track consisting of sheet metal bent into a slotted tube and having its contiguous edges bent radially outward to give additional rigidity to the track, of adjustable supports therefor secured to the middle portion and one end of the track, whereby the otherwise unsupported end may be vertically adjusted simultaneously with the adjustment of the said middle portion and supported end, substantially as described.

6. In a traveling hanger, a spherical roller consisting of two hemispherical parts each of the parts having a central boss upon its flat surface, a hanger strap having a ring surrounding the bosses, balls contained between the conical faces of the bosses and the inner surface of the ring, a bolt for drawing the parts of the roller together, and a lock nut engaging the bolt and contained in a recess in one of the parts of the roller, substantially as described.

7. The combination of a roller, consisting of two hemispherical parts with conical bearing surfaces projecting from their flat sides and provided with means for adjusting these parts together, a hanger strap formed into a

ring at one end with a ball groove on its inferior periphery, and balls between said periphery and the conical surfaces, substantially as described.

5. S. In a traveling hanger for doors, the combination with a door, of a plate secured thereto and provided with a slot and with shoulders on its lower face adjacent to the slot, a track, a roller therefor, a hanger strap suspended from the said roller and having a

threaded stem passing through the slot in the plate, and a nut mounted on the stem, beneath the plate, substantially as described.

Signed by me, in New York city, this 23d day of August, 1894.

JAMES T. McCABE.
